UNITED STATES PATENT OFFICE.

GEORGE J. MULLER, OF BALTIMORE, MARYLAND.

COMBINED FENCE-POST AND TAKE-UP.

1,105,369.

Specification of Letters Patent. Patented July 28, 1914.

Application filed April 1, 1914. Serial No. 828,784.

To all whom it may concern:

Be it known that I, GEORGE J. MULLER, a citizen of the United States, and resident of Baltimore, in the State of Maryland, have 5 invented certain new and useful Improvements in Combined Fence-Posts and Take-Ups, of which the following is a specification.

This invention has for one of its objects 10 to provide a post which will serve not only the purpose of supporting wire fencing of any kind, but will serve to take up or yield slack in the fencing at any time and will hold the fencing releasably, so that it can 15 be readily removed, as for placing the fencing in a different position, or for opening up one or more panels to establish communication past the fence.

A further object is to construct the fence 20 post with a combined retaining and tensioning means, that shall be durable in use and very economical to produce, in that it is made up merely by the assembling of standard or stock materials readily purchasable 25 in the open market.

In carrying out the invention, I employ a channel-iron post having suitably spaced suspending flanges and an adjustably intruding channel-iron retaining and tensioning 30 bar of less transverse dimensions than the post, adapted to enter in between the suspending flanges and to remain out of contact with the post at all adjustments, thus providing a substantially floating slack 35 adjusting member, so that when the fencing is laid across the channel of the post and the combined retaining and tensioning bar is laid over the fencing and drawn into the channel of the post, it not only firmly holds 40 the wire of the fencing, but takes up the portion of the length of the fencing proportional to the degree of intrusion of the retaining and tensioning bar into the channel of the post; means for drawing the retaining and tensioning bar into the channel 45 being provided in the form of bolts passing through the bar and post as well as the interposed fencing, so that they incidentally support the fencing against slipping downward 50 when the clamping action is insufficient for this purpose; the heads of the bolts or their nuts, if preferred, being disposed in the channel of the retaining and tensioning bar so as to resist turning while the bolts 55 are being tightened up from the rear side of the post. The channeled post affords an

advantageous footing for the post in a cement or other sufficiently hard foundation, particularly if the web of the channel be split and the bifurcated end thus provided 60 is spread apart. The bolts for drawing the bar and post together are likewise available for attachment of corner and other braces or bracing wires, and the structural shape of the post or post and bar combined is ad- 65 vantageous for applying an ornamental cap when the post is used in situations that make the same desirable.

The invention will be fully understood upon reference to the accompanying draw- 70 ing, in which—

Figure 1 is a front view, Fig. 2 a side elevation, partly in section, and Figs. 3, 4 and 5 are top plan views on an enlarged scale 75 of the same, showing the bar in different tensioning positions, in a fence post embodying the features of my invention.

A represents the post, made of structural steel rolled in channel section with comparatively deep flanges *a*, substantially perpendicular to the web or back of the member and having its lower end split at *x* to provide a spreading and bifurcated end to give it a firmer footing in a base B of cement or other sufficiently hard material, in which the 80 post is to be embedded. C represents a combined retaining and tensioning bar also constructed of rolled structural steel having a channel section with straight sides, but of sufficiently less dimensions than the section 85 of the post to adapt the bar not only to enter freely into the channel of the post, but to leave considerable spaces at the sides for the wires D of the fencing which pass over the flanges of the post and under the re- 90 taining bar without bending the wire too 95 abruptly.

E represents bolts provided with faced heads passing through both the bar and post and with suitable nuts by which to 100 draw the bar into the channel of the post a distance sufficient to firmly bind the fencing and as much farther as may be necessary to take up slack in the fencing either at the time the fencing is originally erected 105 or subsequently when the fencing becomes loose from any cause and further tensioning becomes desirable. The holes for the bolts are preferably located in such relation to the horizontal strands of the fencing 110 as to afford vertical support for the latter, at least temporarily when the fencing is

being set up. Either the heads of the bolts or their nuts are placed in the channel of the retaining and tensioning bar, so as to prevent them turning while the bolts are being drawn inward.

The protruding ends of the bolts, as well as the nuts thereon, are available for either tension or strut braces at the corners or elsewhere in the fencing; or special holes and 10 bolts through the post alone may be employed for this purpose.

For fencing very uneven surfaces where it is often necessary to erect a post at a comparatively low level, either an extra 15 length of post may be employed or, if desired, a somewhat larger channel member may be telescoped with the main body of the post and held on by the retaining and tensioning bolts, or by special bolts, as may be 20 desired.

I claim:—

A combined fence post and slack adjuster for flexible metallic fencing composed essentially of two members and means holding 25 them together; to wit, a channel-bar supporting-member having laterally spaced suspending flanges across which the fencing is

to lie suspended and having a free intervening space which avoids obstruction to the intrusion of the fencing; a combined retaining and tensioning member having a bearing extended in the direction of the fencing, through which it rests firmly and without rocking upon the portion of the fencing suspended between said flanges; said retaining 30 and tensioning member being proportioned to avoid contact with the supporting member in all adjustments and to leave between its side walls and said suspending flanges, free spaces in which the suspended portions 40 of the fencing may flex; and drawing bolts passing through the members and adjustably intruding the retaining and tensioning member together with the suspended portions of the fencing into the space between 45 the suspending flanges without biting the fencing between the two members.

The foregoing specification signed at Washington, District of Columbia, this 19th day of March, 1914.

GEORGE J. MULLER.
